Application April 30, 1937, Serial No. 139,922

20 Claims. (Cl. 200—48)

The invention relates to switchgear apparatus in general, and more particularly, to electric oil circuit breakers for controlling high voltage transmission systems.

5 In the circuit breaker art, it has heretofore been the usual practice to provide metal tanks for enclosing the relatively movable contacts and other related parts of the circuit breaker. Large insulator bushings were necessary to insulate the terminals of the breaker from the metal tank; and the tank itself had to be of large dimensions in order to provide sufficient space between the tank and all of the live parts. In high capacity breakers of this type, the metal tank occupies considerable space and requires a very large amount of oil for insulation purposes. The large amount of oil required constitutes a dangerous fire hazard due to the fact that it is apt to be ignited on short circuit or 10 on surges resulting from lightning flashes or other causes and the resulting explosion may spread the burning oil over very large areas.

It has been proposed to use porcelain housings in place of the metal tank in order to reduce the space occupied by the breaker and the amount of oil required. Such an arrangement is usually referred to as a porcelain clad oil-poor circuit breaker. Circuit breakers of this type, while possessing certain advantages over the 15 metal clad structures, are a more or less recent development and much is yet to be desired in the way of a satisfactory structure.

An object of the invention is the provision of an improved porcelain clad oil-poor circuit breaker capable of controlling and interrupting large amounts of electric power, which is simple, safe and reliable in operation, and relatively inexpensive to manufacture and service.

Another object of the invention is the provision of an improved oil circuit breaker in which the contact means are enclosed in a tubular casing of insulating material, and the various parts so arranged and constructed that the breaker occupies a minimum amount of space 20 and requires a minimum amount of oil.

Another object of the invention is the provision of an oil circuit breaker embodying a casing including a central grounded metal housing and a pair of tubular members of insulating material mounted on opposite ends of the housing, each having a terminal adjacent its outer end, circuit controlling means operable within the casing insulated with respect to the casing; the casing being pivotally mounted at the housing 25 on a grounded metal frame so that the

breaker can be disposed in either a horizontal or vertical position for connection with the power line.

Another object of the invention is the provision of an oil circuit breaker embodying an improved unitary contact assemblage including a plurality of serially connected pairs of main contacts, a pair of auxiliary disconnecting contacts, and a common actuating means for the contacts; the entire assemblage being removably mounted in a tubular casing of insulating material to facilitate inspection, replacement, and repair of various parts of the assemblage.

Another object of the invention is the provision of an oil circuit breaker embodying a plurality of pairs of serially connected main contacts with associated mechanically connected arc extinguishing devices, a pair of auxiliary contacts for connecting and disconnecting the main 20 contacts with the line terminal and a common actuating means operable during a circuit opening operation for first simultaneously opening the main contacts and subsequently opening the auxiliary contacts to provide a gap capable of 25 withstanding high voltages and operable during a closing operation for first closing the auxiliary contacts and subsequently simultaneously closing the main contacts; the entire contact assemblage being disposed within a tubular casing of insulating material which occupies a minimum amount of space and requires a minimum 30 amount of oil.

Another object of the invention is the provision of an improved oil circuit breaker as set forth in the preceding paragraph in which the unitary contact assemblage is secured to a metal cap chamber which is removably mounted on one end of the insulating casing whereby the entire assemblage may be readily removed from the casing for inspection, repair or replacement; the opposite end of the casing being secured to a metal housing which supports a conductor insulated from the housing by a condenser bushing, the conductor having a separable electrical connection with the contact assemblage to permit removal of the assemblage.

Another object of the invention is the provision of a circuit breaker embodying a casing including a central metal housing and a pair of substantially tubular columns of vitreous insulating material at the opposite ends thereof having their inner ends abutting the opposite ends of the housing; with a novel means including a tube of molded insulating material extending 35 40 45 50 55

through the casing for holding the columns in compression against the central housing. The tube acts as a strain connection between the outer ends of the columns and receives a unitary contact assemblage which is removably mounted within one end thereof which is drilled out to receive the assemblage. The remaining portion of the tube has condenser foils embedded therein so that the tube serves as a condenser bushing for insulating a conductor which extends therethrough for connection with the contact means of the assemblage, from the casing.

The novel features that are considered characteristic of the invention are set forth in particular in the appended claims. The invention itself, however, both as to structure and operation, together with additional objects and advantages thereof will be best understood from the following detailed description of one embodiment thereof when read in connection with the accompanying drawings, in which:

Figure 1 is a side elevational view of a single pole circuit breaker embodying the features of the invention.

Fig. 2 is a front elevational view of the breaker shown in Fig. 1.

Fig. 3 is a side elevational view at reduced scale of the breaker shown in Fig. 1, in which the breaker is shown mounted in a horizontal position.

Fig. 4 is an enlarged fragmentary view partly in section and partly in elevation, illustrating certain structural details of the breaker shown in Fig. 1.

Fig. 5 is a view similar to Fig. 4 but on a smaller scale illustrating the manner in which the contact assemblage may be removed from the casing for inspection, repairs or replacement.

Fig. 6 is an enlarged view, partly in section and partly in elevation, of a portion of the contact assemblage.

Fig. 7 is a plan view of the structure shown in Fig. 6, and,

Fig. 8 is a fragmentary view, partly in section and partly in elevation, of the conductor which is adapted for electrical connection with the contact assemblage, and the condenser bushing associated therewith for insulating the conductor from the central metal housing.

Referring to the drawings and particularly to Figs. 1, 2 and 3 thereof, the single pole circuit breaker illustrated is supported by a metallic frame indicated generally at 9. The frame comprises a plurality of channel bars 11 and connected bracing members 13 arranged in the manner illustrated in Figs. 1, 2 and 3 and connected together by bolts or by welding.

The frame is provided at its upper end with a pair of spaced parallel bearing plates 15 for pivotally supporting the casing of the breaker indicated generally at 17.

The casing of the circuit breaker comprises a central hollow open-ended metal housing 19 and a pair of substantially tubular columns 21 and 23 of vitreous insulating material, such as porcelain or the like, clamped to the opposite ends of the central housing so as to project in opposite directions in substantial alignment.

The central housing is pivotally supported by means of trunnions 25 which pass through the sides of the housing and through openings provided in the bearing plates 15. The central housing 19 is provided with a pair of parallel plates 27 rigidly secured on opposite sides of the housing. The plates 27 are secured to the bearing plates 15 by means of bolts 29 which pass through

openings provided in the plates 15 and 27. The breaker casing may be secured in either a vertical or a horizontal position, and for this purpose the bearing plates 15 are provided with a plurality of horizontally arranged openings for receiving the bolts 29 when the breaker is to be mounted in the vertical position, and a plurality of vertically arranged openings for receiving the bolts when the casing is to be mounted in horizontal position. The breaker casing is shown mounted in horizontal position in Fig. 3. This feature is particularly desirable for the reason that in certain applications it may be desirable to have the breaker mounted in a vertical position for connection with the power lines, whereas, in other applications, a horizontal mounting may be preferred.

A tubular member 35 of molded insulating material extends through the casing 17. The upper end of the member 35 is drilled out at its upper end, as shown in Figs. 4 and 8, to provide a recess 36 for receiving the circuit interrupting units of a unitary contact assemblage which will be described hereinafter. A flanged metal ring 37 is secured to the upper end of the tubular member 35. The ring 37 may be pressed on the end of the tube, threaded thereon, or secured in any other suitable manner.

An expansion ring member 38 of resilient conducting material, having a C shaped cross section, is secured to the flange of the ring 37 by means of bolts 39. The under side of the expansion ring member 38 abuts the upper end of the insulating column 21. The top portion of the expansion ring member 38 is provided with a peripheral flange on which is mounted a closure 40 secured to the ring member by suitable bolt fastenings. The flange of the ring member 38 is also provided with a terminal 33 formed integral therewith, for connecting the breaker to a power line.

The upper end of the tubular molded insulating member 35 is adapted to receive and support a unitary contact assemblage indicated generally at 41 (see Fig. 5).

Referring to Fig. 4, the unitary contact assemblage 41 comprises, in general, a plurality of interconnected circuit controlling and arc extinguishing devices 43, a disconnecting switch 45, and a common actuating means indicated generally at 47 for the circuit controlling devices 43 and the disconnecting switch 45.

Each of the interconnected circuit controlling devices 43 comprises, in general, a stationary contact 49, a cooperating movable contact 51, arc extinguishing means indicated generally at 53, and a straight line linkage mechanism indicated generally at 55 for operating the movable contact. Any suitable circuit controlling device of this type may be used. One particularly effective form of circuit controlling device of this type that may be used is shown and described in detail in the copending application of Roswell C. Van Sickie, Serial No. 83,600, filed June 5, 1936 now Patent No. 2,138,391, issued November 29, 1938, and assigned to the assignee of this invention. Another form of circuit controlling device that may also be used is shown and described in the copending application of John B. MacNeill, Serial No. 42,183, filed September 28, 1935, and also assigned to the assignee of this invention.

Any suitable type of arc extinguishing means for the contacts may be used. Several types of arc extinguishing means that may be used are shown and described in detail in the above men-

tioned copending applications. Another very effective type of arc extinguishing means that may be used is shown and described in detail in Patent 2,095,301, issued October 12, 1937, upon an application of Howard M. Wilcox, Serial No. 83,597, filed June 5, 1936, and assigned to the assignee of this invention.

Each circuit controlling device 43 is enclosed by a cylindrical shell 57 of insulating material and by end plates 59 of conducting material. The circuit controlling devices are mechanically connected together by means of tie brackets 61 secured to the end plates of the adjacent unit by means of nut and bolt assembly 63. The relatively movable contacts of the circuit controlling devices are connected in series by means of flexible shunt conductors 65 which connect the stationary contact of one device with the movable contact of the next adjacent device. The movable contacts 51 and their straight line operating linkages 55 are connected for movement together by means of an insulating rod 67 which passes through the aligned central openings provided in each of the circuit controlling devices 43, the rod 67 being connected to each of the actuating linkages by means of pivot pins 73.

The upper end of the insulating rod 67 has a spring loaded contact member 71 secured thereto by means of the pin 73 which connects the rod with the actuating linkage 55 for the movable contact of the upper circuit controlling device 43. The contact member 71 includes a plurality of contact fingers 75 arranged in a circle and biased toward the center of the circle by means of circular coil springs 76. Inward movement of the contact fingers 75 is limited by their engagement with the body portion 78 of the contact member. The contact member 71 forms the stationary contact of the disconnecting switch 45, and is electrically connected with the movable contact 51 of the upper circuit controlling device 43.

The insulating shells 57 of the upper circuit controlling device 43 is secured to an insulating collar 79 which is, in turn, secured to the spider of a metal cap member 81. A movable contact 83 is mounted for vertical sliding movement in the cap member 81 for cooperation with the contact member 71 carried by the upper end of the insulating rod 67. The contacts 83 and 71 thus form the relatively movable contacts of the disconnecting switch 45.

The common actuating mechanism for the circuit controlling devices 43 and for the disconnect switch 45 comprises a lever 85 pivotally mounted within the cap member 81. The central portion of the lever 85 is connected with the movable contact 83 of the disconnecting switch by means of a pin and slot connection which provides straight line motion of the contact 83 when the lever 85 is rocked about its pivot. A flexible shunt 86 electrically connects the movable contact 83 with the cap member 81 which is in turn connected to the line terminal 33.

When the disconnecting switch 45 is closed as shown in Fig. 4, the fingers 75 of the contact member 71 frictionally engage the movable contact 83 with a relatively high pressure, so that the movable contact 83 and the insulating rod 67 are connected for movement together. The rod 67 is urged in an upward direction by means of a compression spring 84 (Fig. 6) which engages the lower end of rod 67 so as to bias all of the movable contacts 51 toward their open circuit position. The spring 84 also functions to maintain contact member 71 in engagement with the

movable contact 83 of the disconnecting switch during the first part of the circuit opening operation as will be described hereinafter.

An accelerating tension spring 87 is connected to the upper end of the movable contact 83 for accelerating the movement of the contacts during the operation of the circuit breaker.

It will be understood from the structure thus far described that, when the lever 85 is rotated in the clockwise direction about its pivot pin, the movable contact 83 is moved upwardly and due to the frictional engagement of the spring biased fingers 75 with the movable contact and the force exerted by the spring 84, the rod 67 is also moved upwardly to effect simultaneous opening of the relatively movable contacts of each circuit controlling device 43; all of the movable contacts 51 being moved upwardly by their straight line linkage mechanisms 55 which connect the same with the insulating rod 67. As the movable contacts 51 are separated from their cooperating contacts 49, the arc formed incident to their separation is quickly extinguished by means of the arc extinguishing means 53. After the movable contacts have reached the limits of their upward movement, further rotation of the lever 85 separates the movable contact 83 from the spring loaded contact member 71 so as to disconnect the contacts of the circuit controlling devices from the movable contact 83. The lever 85 is capable of rotating a sufficient amount to introduce a large gap, capable of withstanding high voltages, between movable contact 83 and spring loaded contact 71.

When the lever 85 is rotated in a counter-clockwise direction after a circuit opening operation, the movable contact 83 is first moved into firm frictional engagement with the fingers of the spring loaded contact 71 to close the disconnecting switch. Further counter-clockwise rotation of the lever 85 moves the rod 67 downwardly against the bias of the spring 84 to effect simultaneous closing of all the movable contacts 51 on their cooperating stationary contacts 49. This simultaneous closing operation is effected through the agency of the straight line linkage mechanisms 55 which connect the insulating rod 67 with each of the movable contacts.

For the purpose of equally distributing the voltage drops across the relatively movable contacts of the several circuit controlling devices 43, the upper portion of the molded insulating tube 35 may be provided with a plurality of condenser shields (not shown) embedded therein and spaced in such a manner as to provide equal distribution of the voltages across the several contacts during arc extinction and also following circuit interruption when the contacts are in the open position. A preferred form of condenser shielding arrangement in which the condenser shields are embedded in an insulating tube is shown and described in detail in the copending application of Benjamin P. Baker, Serial No. 83,260, filed June 3, 1936, and assigned to the assignee of this invention. The condenser shielding arrangement effectively prevents any one of the circuit controlling devices from assuming more than its share of the impressed voltage.

The lowermost circuit controlling device 43 has secured to the under side thereof a spring loaded contact 91 which is adapted to engage the upper end of a conductor which will hereinafter be described. The spring loaded contact 91 is somewhat similar to the previously described contact member 71. It consists of a body por-

tion 93, which is threaded onto the lower end of an insulating tube 95 which receives the insulating rod 67 and the biasing spring 84, and a plurality of circularly arranged contact fingers 91. The contact fingers 91 are biased inwardly by means of a pair of circularly arranged springs 99 disposed in recesses provided in the backs of the contact fingers 91. The spring loaded contact 91 is electrically connected to the stationary contact 49 of the lowermost circuit controlling device 43 by means of a conductor 101.

The cap member 81 which carries the contact assemblage 41 is removably secured to the conducting expansion ring member 31 by means of bolts 103. By this arrangement the entire contact assemblage including the cap member 81 may be removed from the molded insulating tube 35 in order to inspect, repair or replace the various parts of the contact assemblage. The spring loaded contact 91 forms a separable electrical connection for connecting the circuit controlling devices with a conductor 105 extending within the casing 17 so as to permit removal of the entire contact assemblage without disconnecting any conductor wire.

A hollow cylindrical conductor 105 extends through the body portion of the tubular molded insulating member 35. The insulating tube 35 is formed of a series of tightly wound and compacted layers of paper or cloth impregnated with a phenolic condensation product the layers being wound tightly upon the hollow conductor 105 so that the finished tube 35 is rigidly secured on the conductor 105. The upper end of the conductor extends through the body of the tube 35 to a point substantially flush with the bottom of the drilled recess 36 and has a contact plug 106 threaded therein which is adapted to be engaged by the fingers of the spring loaded contact 91 of the contact assemblage. It will thus be seen that the contact means of the contact assemblage have a separable electrical connection with the upper end of the conductor 105, which permits removal of the unitary assemblage 41 from the tube 35. A terminal cap 107 is threaded on the lower end of the conductor 105, which serves to connect the breaker to an external line or conductor.

A plurality of stepped and spaced condenser foils 111 are imbedded in the body portion of the molded insulating tube 35 (Fig. 8). These foils together with the insulation of the tube 35 serve to effectively insulate the conductor 105 with respect to the casing 17 and particularly the central metal housing portion 19 thereof. It will thus be seen that the body portion of the tube 35 with its embedded condenser foils 111 forms a condenser bushing for the conductor 105.

A second annular expansion ring member 109 encircles the lower end of the conductor 105. The upper side of the ring member 109 is adapted to engage the lower end of the vitreous insulating column 23 in abutting relation. A nut 110 is threaded on the lower end of the conductor 105 between the cap terminal 107 and the lower side of the expansion ring member 109.

It will be noted at this point that the expansion ring member 31, the insulating tube 35 and the conductor are all rigidly secured together so that when the nut 110 is tightened against the ring member 109 the vitreous insulating columns 21 and 23 are clamped between the ring members 31 and 109 in compression against the ends of the central metal housing 19. The insulating tube 35 thus acts as a strain connection

between the outer ends of columns 21 and 23 always transmitting compressive forces thereon to hold them firmly against the central housing. The expansion members 31 and 109 being of resilient material and C shaped in section permit relative expansion between the vitreous insulating columns and the conductor 105 and tube 35.

The tube 35 in addition to its function as a mechanical strain connection serves to receive and support the unitary contact assemblage which is removably mounted in one end thereof; the tube 35 also functions as a condenser bushing for insulating the conductor 105 with respect to the casing. This arrangement provides a very desirable and economical breaker structure which materially reduces the number of parts required.

Suitable rubber or cork gaskets 119 are interposed at the joints between the insulating columns 21 and 23, the ring members 31 and 109, the central housing 19 and the closure 116. These gaskets permit the several parts to be drawn tightly together to provide an oil tight casing. Other well known types of sealing means may be used to insure oil tightness of the casing if desired.

The windings 113 of a bushing type current transformer are disposed within a compartment formed in the central metal housing 19, the windings encircling the tube 35 and the conductor 105, so as to be energized by the current flowing through the conductor. This arrangement eliminates the necessity of providing separate tanks and bushings for the current transformer.

The casing of the circuit breaker is filled with an insulating arc extinguishing liquid of any suitable type such as oil which is adapted to be supplied to the casing through a filler inlet 115 carried by the oil tight end closure 116 secured to the ring 31. The liquid may be drained from the casing through an outlet closed by a drain plug 117. The oil is brought to a level sufficient to cover the contacts of the disconnecting switch 46.

A pair of liquid level gauges 118 are provided for the casing one being secured to the ring member 31 and the other to the central metal housing 19. The gauge 118 secured to the ring member 31 serves to indicate the level of the liquid when the breaker is disposed in a vertical position while the gauge secured to the central metal housing serves this purpose when the breaker is disposed in the vertical position. It is important that the level of the insulating liquid always be maintained above the contacts of the disconnecting switch 46. If desired suitable pumping means may be provided for circulating the insulating liquid through the casing.

The operating means for the circuit breaker includes an insulating rod 121 disposed between the outer tubular column 21 and the inner tubular insulating member 35, detachably connected at its upper end to the free end of the lever 85 and connected at its lower end to a crank arm 122 rigidly secured to the transverse shaft 120. Shaft 120 extends through the walls of the housing 19 and is adapted to be operated by linkage mechanism 127. The linkage mechanism is connected by bell crank lever 123 with the upper end of a pull rod 126. The lower end of the pull rod is connected to a suitable operating mechanism enclosed in a casing 128. The operating mechanism within the casing 128 may be of any suitable type including a motor or solenoid operated closing means, a latch for restraining the breaker in

closed circuit position, a spring means for biasing the pull rod to open circuit position, and a tripping means. A bell crank lever 135 is connected with the linkage mechanism 127 for the purpose 5 of connecting similar additional breaker units to the operating mechanism within the casing 133 for gang operation thereby.

The electrical circuit through the breaker is as follows: From the terminal 107 the current flows 10 through the conductor 105 to the contact member 91 through the serially connected circuit controlling devices 43 and disconnecting switch 45, through the movable contact 83, flexible shunt conductor 86 and the metal cap member 81 to the 15 line terminal 33. It will be noted that both the terminals are effectively insulated from the grounded central metal housing 19 by means of the tubular insulating columns 21 and 23, the conductor 105 being insulated from the metal 20 housing by means of the insulating tube 35 with its condenser foils. The leads from the current transformer may be connected to suitable indicating instruments or relays as may be desired. The condenser foils 111 may be tapped to provide 25 a source of potential for relaying and metering purposes, if desired.

The operation of the circuit breaker is as follows: With the breaker in closed circuit position as shown in Figs. 1, 2 and 4, let it be assumed that it is desired to open the breaker. The operating rod 131 is moved in an upward direction by the operating mechanism. This upward movement of the rod 131 operates through the bell crank 129 and the linkage mechanism 35 127 to cause upward movement of the insulating rod 121 within the tubular insulating member 21 to rotate the lever 85 in a clockwise direction about its pivot support. The clockwise rotation of the lever 85 allows the insulating rod 67 of 40 the contact assemblage 41 to be moved in an upward direction by the force exerted by the biasing spring 84. Since each of the movable contacts 51 of the circuit controlling devices 43 is connected through its straight line linkage mechanism 55 with the insulating rod 67, the upward movement of the rod 67 causes simultaneous movement of all of the movable contacts 51 to their open circuit position. When the movable contacts 51 have reached their full open circuit 50 position, any further upward movement of the insulating rod 67 is prevented since it has reached the upward limit of its movement. Further upward movement of the insulating rod 121 by the operating mechanism causes the movable contact 55 83 of the disconnecting switch 45 to separate from the stationary spring loaded contact 71, so as to disconnect the relatively movable contacts of the circuit controlling devices from the line terminal 33. The contact 83 separates a sufficient distance from the spring loaded contact 71 to provide a gap in clean oil which has not been subjected to arcing and capable of withstanding extremely high voltages, so that the circuit controlling devices are protected from surges 65 due to lightning flashes and other causes in the open circuit position of the breaker. In closing the circuit breaker, the operating rod 131 is moved downwardly by the operating mechanism. The downward movement of the rod 131 is transmitted through the bell crank 129 and linkage mechanism 127 to the insulating rod 121 within the tubular casing 21 to cause downward movement 70 of said insulating rod.

During the first part of the downward closing 75 movement of the insulating rod 121, the movable

contact 83 is moved into frictional engagement with the spring loaded contact 71 to close the disconnecting switch 45. Further downward movement of the insulating rod 121 after the contact 83 has completely engaged the spring loaded contact 71, causes downward movement of the central insulating rod 67. Since the insulating rod 67 is connected by the straight line linkage mechanisms 55 with each of the movable contacts 51 of the several circuit controlling devices, the 10 downward movement of the rod 67 effects simultaneous movement of all of the movable contacts 51 to their closed circuit position in engagement with their cooperating stationary contacts 49. The circuit breaker is now completely closed and 15 is held in closed circuit position by means of a latch in the casing of the operating mechanism 133.

When the latch of the operating mechanism is released to trip the breaker, the rod 131 is released, permitting the biasing spring means of the 20 operating mechanism to open the breaker in the same manner as previously described.

The specific structure of the casing of the circuit breaker with its central metal housing and 25 oppositely extending tubular insulating columns provides a compact circuit breaker which occupies a relatively small amount of space and which requires only a small amount of insulating arc extinguishing liquid; and the provision of the 30 molded insulating tube with its condenser foils for insulating the conductor from the central metal housing permits the breaker to be supported by a metal frame or any other type of grounded supporting means. The feature of pivotally mounting the circuit breaker casing permits the same to be mounted in either a vertical or horizontal position for connection with the power line. 35

The unitary contact assemblage with the means for removably mounting the same in the tubular 40 insulating member 35 with the circuit controlling devices disposed within the tubular insulating member, provides a very desirable construction which greatly facilitates inspection, repair or replacement of the various parts of the contact assemblage. The contact assemblage may be removed by unscrewing the bolts 103 and disconnecting the insulating rod 121 from the free end of the lever 85. The entire contact assemblage 41 including the cap member 81 may then be 50 withdrawn from the tubular insulating member 35. This removal of the contact assemblage is accomplished without the disconnection of any circuit conductors due to the separable electrical connection of the lowermost circuit controlling 55 device 43 with the conductor 105.

The provision of the disconnecting switch 45 and the common actuating means for operating the circuit controlling devices and the disconnecting switch in a predetermined sequence provides 60 a highly desirable safety factor which protects the circuit breaker when in the open circuit position from surges due to lightning flashes and other causes. It will be noted that the disconnecting 65 switch provides an auxiliary break in clean oil at the top of the insulating member 21.

While the invention has been shown and described in accordance with the provisions of the patent statutes, it is to be understood that various 70 changes may be made in the structural details without departing from the spirit of the invention. I desire, therefore, that the language of the accompanying claims be given the broadest reasonable interpretation permitted by the prior art. 75

I claim as my invention:

1. In a circuit breaker for high voltage power circuits, a tubular casing of insulating material, a line terminal supported on said casing adjacent one end thereof, supporting means for said casing, a unitary contact assemblage disposed within said casing including at least one pair of relatively movable main contacts and a pair of disconnecting contacts arranged end for end in substantially axial alignment, one contact of said disconnecting contacts being connected with said line terminal, a support member removably secured to said casing adjacent said line terminal, and means for mounting said contact assemblage upon said support member, said contact assemblage being removable with said support member from said casing as a unit.
2. In a circuit breaker for high voltage power circuits, a tubular casing of insulating material having a line terminal adjacent one end thereof, supporting means for said casing, a unitary contact assemblage disposed within said casing including at least one pair of relatively movable main contacts, a pair of disconnecting contacts connected in series with said main contacts and actuating means for operating said pairs of contacts, one of said disconnecting contacts being electrically connected to said line terminal, and a cap member removably mounted on the terminal end of said casing, said contact assemblage being secured to said cap member so as to be removable therewith.
3. In a circuit breaker for high voltage power circuits, a tubular casing of insulating material having a line terminal adjacent one end thereof, supporting means for said casing, a unitary contact assemblage disposed within said casing including at least one pair of relatively movable contacts, a cap member removably mounted on the terminal end of said casing, said contact assemblage being secured to said cap member so as to be removable therewith, means including said cap member for connecting one of said contacts with said line terminal.
4. In a circuit breaker for high voltage power circuits, a tubular casing of insulating material, a line terminal supported on said casing adjacent one end thereof, supporting means for said casing, a unitary contact assemblage disposed within said casing including at least one pair of relatively movable contacts and actuating means therefor, said unitary contact assemblage being removable through the line terminal end of said casing, one contact of said pair adapted to be connected with said line terminal, means for removably mounting said contact assemblage adjacent the terminal end of said casing, and a stationary conductor extending into said casing from the other end thereof and having a separable electrical connection with the other contact of said pair, said separable connection automatically breaking the connection between said conductor and said other contact upon withdrawal of said contact assemblage from said casing.
5. In a circuit breaker for high voltage power circuits, a tubular casing of insulating material having a line terminal adjacent one end thereof, supporting means for said casing, a unitary contact assemblage disposed within said casing including at least one pair of relatively movable contacts, a cap member removably mounted on the terminal end of said casing, said contact assemblage being secured to said cap member so as to be removable therewith, means including said cap member for connecting one of said contacts with said line terminal, and a stationary conductor extending into said casing having a separable electrical connection with the other contact of said pair upon removal of said contact assemblage from said casing, said stationary conductor being removably secured to said casing.
6. In a circuit breaker for high voltage power circuits, a casing including a central metal housing and a pair of substantially tubular members of insulating material secured at opposite ends of said housing so as to extend in opposite directions in substantial alignment, each of said members having a terminal adjacent the outer end thereof, a unitary contact assemblage including at least one pair of relatively movable contacts and actuating means therefor disposed in one of said insulating members, means releasably mounting said assemblage adjacent the terminal end of said one of said insulating members, one of said contacts adapted to be electrically connected to the terminal of said last mentioned insulating member, a conductor extending longitudinally through said casing having a releasable electrical connection with the other contact of said pair so as to permit removal of said assemblage from said one member upon being released from said mounting means, and a condenser bushing for insulating said conductor with respect to said casing.
7. In a circuit breaker for high voltage power circuits, a casing including a central grounded metal housing and a pair of tubular insulating members secured to the opposite ends of said housing, each of said members having a terminal adjacent the outer end thereof, a unitary contact assemblage including at least one pair of relatively movable contacts and actuating means therefor disposed in one of said insulating members, a metal cap member removably mounted on the outer end of said last mentioned insulating member, said assemblage being secured to said cap member so as to be removable therewith, means including at least a portion of said cap member for electrically connecting one of said contacts with the terminal on said last mentioned insulating member, a conductor extending longitudinally through said casing having a separable electrical connection with the other contact of said pair, said connection being automatically disengageable upon removal of said assemblage from said last mentioned insulating member, and a condenser bushing for insulating said conductor with respect to said casing.
8. In a circuit breaker for high voltage power circuits, a casing including a central metal housing and a pair of substantially tubular members of insulating material secured at opposite ends of said housing so as to extend in opposite directions in substantial alignment, each of said members having a terminal adjacent the outer end thereof, a unitary contact assemblage including at least one pair of relatively movable contacts and actuating means therefor disposed in one of said insulating members, means removably mounting said assemblage adjacent the terminal end of said one insulating member, one of said contacts adapted to be electrically connected to the terminal of said last mentioned member, a conductor extending longitudinally through said casing having an automatically separable electrical connection with the other contact of said pair upon removal of said assemblage from said one insulating member, a condenser bushing for insulating said conductor with respect to said casing, and a current transformer.

- disposed in said casing and encircling said bushing for energization by the current flowing in said conductor.
9. A circuit breaker for high voltage power circuits comprising a casing including a central metal housing and a pair of tubular insulating members mounted at opposite ends of said housing, a terminal supported by each insulating member adjacent the outer ends thereof, relatively movable contacts disposed in one of said insulating members, frame means for pivotally supporting said central housing so that said breaker may be disposed in either a vertical or horizontal position.
10. 10. A circuit breaker for high voltage power circuits comprising a casing including a grounded central metal housing and a pair of tubular insulating members mounted at opposite ends of said housing, a terminal supported by each insulating member adjacent the outer end thereof, relatively movable contacts disposed in one of said insulating members one of which is connected to one of said terminals, a conductor extending into said casing for connecting the other said terminal with said contacts, a condenser bushing for insulating said conductor with respect to said central housing, and frame means for pivotally supporting said central housing so that said breaker may be disposed in either a vertical or horizontal position.
11. A circuit breaker for high voltage power circuits comprising a casing including a grounded central metal housing and a pair of tubular insulating casings mounted at opposite ends of said housing, a terminal supported by each insulating casing adjacent the outer ends thereof, relatively movable contacts disposed in one of said insulating casings one of which is connected to one of said terminals, a conductor extending into said casing for connecting the other said terminal with said contacts, a condenser bushing for insulating said conductor with respect to said central housing, frame means for pivotally supporting said central housing so that said breaker may be disposed in either a vertical or horizontal position, and a current transformer encircling said condenser bushing and disposed within said housing for energization by the current flowing in said conductor.
12. In a circuit breaker, a hollow column of vitreous insulating material, a fixed support for the breaker abutting one end of said column, a ring member abutting the other end of said column, means including a substantially tubular casing extending concentrically within said column and connected to said ring member for clamping said column firmly to said support, a contact assemblage including at least one pair of relatively movable contacts, supported solely by said ring member with said contacts disposed within said tubular member.
13. In a circuit breaker, a hollow column of vitreous insulating material, a fixed support for the breaker, means mounting said column with one end thereof abutting said fixed support and for holding the same firmly against the support comprising a substantially tubular member of insulating material extending through said column and having a resilient expansible member secured to one end for abutting the other end of said column so that said column is clamped between said expansible member and said fixed support, and circuit interrupting means disposed within said tubular member and releasably and solely supported thereby at the end adjacent said ex-
- pansible member, said expansible member permitting relative expansion between the column and other parts of the breaker.
14. In a circuit breaker, a hollow column of vitreous insulating material, a fixed support for the breaker abutting one end of said column, a resilient expansible ring member abutting the other end of said column, means including a substantially tubular casing extending concentrically through said column and connected to said ring member for clamping said column firmly to said fixed support, a unitary contact assemblage including at least one pair of relatively movable contacts supported by said ring member and removably mounted within said tubular member.
15. In a circuit breaker for high voltage power circuits, a casing including a central metal housing and a pair of hollow columns of vitreous insulating material having their inner ends abutting the opposite ends of said housing, a substantially tubular member extending substantially through said casing including means having abutting engagement with the outer ends of said columns for firmly clamping said columns to said central housing, circuit making and breaking means mounted within a portion of said tubular member, a conductor extending into said tubular member for connection with said circuit making and breaking means and condenser foils embedded within said tubular member for controlling the voltage distribution between said conductor and said casing.
16. In a circuit breaker, a casing including a pair of hollow columns of weatherproof insulating material and a central fixed support abutting the inner ends of said columns, a substantially tubular member extending substantially through said casing including expansible ring members having abutting engagement with the outer ends of said columns for clamping said columns firmly to said fixed support, a unitary contact assemblage including at least one pair of relatively movable contacts removably mounted within said tubular member, means releasably securing said contact assemblage to one end of said tubular member, a stationary conductor extending into said tubular member having a separable electrical connection with the contact means of the unitary assemblage, said separable connection enabling said contact assemblage to be withdrawn from said tubular member as a unit upon release of said securing means and condenser foils embedded in said tubular member for controlling the voltage distribution between said conductor and said casing.
17. In a circuit interrupter, a casing including a pair of hollow columns of insulating material and a central metallic support abutting the inner ends of said columns, a conductor extending centrally of and into said casing, a condenser bushing surrounding said conductor for insulating it from said casing, said bushing having a recess in one end thereof, a pair of flange members having respective abutting engagement with the outer ends of said insulating columns and respectively secured to the outer end of said conductor and the recessed end of said bushing for holding said insulating columns and support in compression, at least one pair of relatively movable contacts mounted within said recess, means connecting one of said contacts with the inner end of said conductor and means for actuating said contacts to open and closed positions.
18. In a circuit interrupter, a casing including a pair of hollow columns of insulating material

- and a central metallic support abutting the inner ends of said columns, a conductor extending centrally of and into said casing, a condenser bushing surrounding said conductor for insulating it from said casing, said bushing having a recess in one end thereof, a pair of flange members having respective abutting engagement with the outer ends of said insulating columns and respectively secured to the outer end of said conductor and the recessed end of said bushing for holding said insulating columns and support in compression, a unitary contact structure including at least one pair of separable contacts disposed within said recess, means for releasably securing said contact structure to the flange member adjacent said recess, a plug-in connection between one of said contacts and the inner end of said conductor to enable said unitary contact structure to be withdrawn from said recess upon being released from said flange member.
19. In a circuit interrupter, a casing including a hollow column of insulating material and a metallic support abutting one end of said column, a conductor extending into said casing, a condenser bushing surrounding said conductor for insulating it from said casing, said bushing having a recess in one end thereof, a flange member secured to the recessed end of said bushing and

having abutting engagement with the other end of said insulating column for holding said column and support in compression, at least one pair of separable contacts mounted within said recess, means connecting one of said contacts with the inner end of said conductor, and means for actuating said contacts to open and closed position.

20. In a circuit interrupter, a casing including a hollow column of insulating material and a metallic support abutting one end of said column, a conductor extending into said casing, a condenser bushing surrounding said conductor for insulating it from said casing, said bushing having a recess in one end thereof, a flange member secured to the recessed end of said bushing and having abutting engagement with the other end of said insulating column for holding said column and support in compression, a unitary contact structure including at least one pair of separable contacts disposed within said recess, means for releasably securing said unitary contact structure to said flange member, a plug-in connection between one of said contacts and the inner end of said conductor to enable said unitary contact structure to be withdrawn from said recess upon being released from said flange member.

J. B. MacNEILL.
